EYEGLASS FRAME FRONT

Henry E. Gaboriault, 73 Ledge St., Central Falls, R.I.

Filed Sept. 24, 1964, Ser. No. 81,859

Term of patent 14 years

(Cl. D57—1)

FIG. 1

FIG. 2

FIG. 1 is a front elevation of an eyeglass frame front showing my new design; and

FIG. 2 is a section taken on the line 2—2 of FIGURE 1.

The dominant features of my design reside in the portions shown in full lines.

The drawing is stippled to indicate contrast.

I claim:

The ornamental design for an eyeglass frame front, as shown and described.
